UNITED STATES PATENT OFFICE.

HERBERT A. MEGRAW, OF NEW YORK, N. Y.

MINING-SCREEN.

1,090,933

Specification of Letters Patent. Patented Mar. 24, 1914.

Application filed May 1, 1913. Serial No. 764,787.

To all whom it may concern:

Be it known that I, HERBERT A. MEGRAW, a citizen of the United States, and a resident of the borough of Manhattan, in the city, county, and State of New York, have invented certain new and useful Improvements in Mining-Screens, of which the following is a specification.

In the wet metallurgy of various metals, including gold, silver, copper, lead, zinc and some of the less important minerals, it is necessary to separate the ground rock or ore into classes according to their sizes in order that the different classes or sizes may receive different treatment. After a preliminary crushing some of the rock may be reduced to the desired degree of fineness while another part will be in sizes too large to be efficiently treated by the particular process in view. It is then necessary to separate the finely ground portion from that which is not sufficiently fine, so that the latter may receive further grinding. Or it may be that each class or size of material requires different metallurgical handling, as is the case in concentration, where each size should be separately worked upon, or in cyanidation, where the fine portion must be treated in one way and the coarse portion in an entirely different manner. This separation has been accomplished in different ways, more particularly by screens or sieves of which many forms have been in use, but none of which has given entire satisfaction. The requirements of a satisfactory screen which the present invention aims to fulfil are: durability and strength of construction, capacity to handle a large amount of material quickly, avoidance of blockading or filling of the screen, small power requirement, minimum requirement in respect of grade or height in installation, and convenience, efficiency and economy in leading the material to and away from the screen.

A primary object is the avoidance of wear, not only of the screen as a whole, but more particularly of the screen fabric itself, thus especially fitting the invention for fine screening, for which the fabric is frequently of great delicacy and therefore peculiarly subject to wear, both from the action of the particles of ore and from the movement or movements imparted to the screen. In my screen the action of the ore particles is minimized and the movement of the screen

is simply one of rotation, without vibration or bumping or bending of the wire mesh.

Heretofore in rotary ore sizing screens for fine screening wear has been very rapid and it has been very difficult to keep the meshes from becoming clogged, because the sliding of the ore on the fabric is not only immediately destructive but multiplies the opportunities for blockading, to relieve which latter condition agitation or vibration or disturbance of the screen and fabric of some sort has been resorted to, with the result of greatly hastening their destruction. According to my invention, the sliding of the ore on the fabric is limited by means in the nature of shelves, which also serve to remove the over-size material from the screening region, the organization being such that successive portions of the pulp are in effect deposited gently upon a succession of screens, the under-size being permitted to pass through at once and the over-size being carried upward. The screen is tubular or elongated and is rotatably supported near its ends or at suitably spaced points by bearings, such as rollers, which leave its interior and ends unobstructed; the pulp is led in at one end and deposited upon and lengthwise of the bottom of the screen by an entry launder adjacent the lowest part of the screen; id the over-size is carried onward in the same direction by an over-size discharge launder to which the material which does not pass through the meshes is elevated and delivered by the longitudinal wear-preventing shelves. The fact that the entry and over-size launders extend in the same direction, adapting the screen for through-movement of the material, in at one end and out at the other, though not along the bottom of the screen, essentially distinguishes this screen from any construction which requires the pulp to double upon its track. My screen provides for direct travel of the ore pulp, without manual or mechanical effort, without special elevating machinery, and without additional wear and loss of grade due to turns or angles in the launders, and is adapted to make the most advantageous use of natural grade, or to require the least amount of artificial grade or height in installation.

In the drawings: Figure 1 is a vertical longitudinal section; Fig. 2 is a vertical cross-section on the line 2-2 of Fig. 1; Fig. 110

3 is a similar section on the line 3—3 of Fig. 1; Fig. 4 is a detail sectional plan on an enlarged scale of the entry launder, showing a form of means for distributing the incoming material uniformly; and Fig. 5 is an enlarged detail view showing a manner of holding the longitudinal edges of the screen fabric.

The sieve or screen proper 10 is of hollow elongated or tubular form, and is desirably constructed by supporting the screen material 11 on a frame or skeleton structure consisting of end ring castings 12 and connecting members 13, which may be in the nature of angle irons as shown. The screening medium is curved around the members 13, and its longitudinal edges are desirably clamped as indicated in Fig. 5. Manifestly the screen material may be secured to the supporting structure intermediate these edges if desired, and while it is shown brought into cylindrical tubular form it will be understood that it might be polygonal in cross-section with equivalent results.

The invention is designed for fine screening, for which a wire fabric is employed, which may vary from 4 to 100 mesh, or smaller, according to the fineness of the material to be sized.

The sieve thus constructed is supported on bearings which leave both its ends and its interior unobstructed, this being important for the purposes of my invention. Thus, the ring castings 12 are shown provided with tracks 14 which rest on grooved rollers 15 mounted on blocks 16, at opposite ends of the sieve. Driving of the screen is advantageously provided for by means of a worm 17 at the top, which meshes with a worm gear 18 formed on one of the ring castings 12 outside of the track flange 14, where the gearing is largely protected from dirt and moisture. The sieve is supported substantially horizontal, and the pulp does not travel lengthwise over its bottom.

Interiorly the sieve has provisions for limiting the lateral sliding of the material, which consisting of ground rock and particles of metal is naturally abrasive, and for elevating the oversize material, which does not pass through the meshes of the screening medium, for the purpose presently to be described. The simplest form of these provisions is that indicated, consisting of flat shelves or inward projecting wings 19, which are shown secured to the angle irons 13, though obviously they might be integral therewith so as to form elongated flanges of the angle irons. The spacing of these shelves and their width or depth will obviously depend upon the special conditions of each case; but in general the distance measured circumferentially between them on the screen material should be such as to reduce as much as possible the sliding and rolling

of the particles, so as to minimize the wear on the medium, while at the same time permitting such range of movement as may be necessary to insure effective separation. The shelves extend the full length of the sieve or substantially so, and carry up the larger particles of the pulp, which is distributed the full length of the bottom of the sieve by the means now to be described.

The material is supplied to the screen, substantially equally throughout its length, by means of an entry launder or trough 20, which enters the screen at one end and extends substantially the full length thereof, in the lower part and preferably centrally of the screen. This launder leads from any suitable source of supply and is suitably pitched, according to the rate of flow desired and the consistency of the fluid mixture of ground ore and water. It is preferably closed at its lower end and is provided with suitable means for causing the material to overflow or discharge substantially equally at different points along its length. As shown it has a multiplicity of discharge openings 21 arranged in longitudinal series along one side and adjacent its bottom, and with these openings are associated a number of vanes 22 in the interior of the trough, the same being mounted so that they can be turned more or less and in different degrees to secure the exact distribution desired. One such directing device is shown for each opening, but obviously fewer could be employed. Any suitable provision may be made for holding the angular adjustment of the vanes 22. For example, they may be pivoted on ordinary wood screws 28, which are screwed into the bottom of the entry launder and may be readily tightened or loosened.

A discharge launder 23 is located above the entry launder, and likewise extends the full length of the sieve. It is inclined in the same direction as the entry launder, so as to lead the oversize material out at the end opposite to that at which the entry launder leads the material in. Its lower projecting portion is shown broken away to indicate that it may extend to any suitable distance or point of discharge. At its upper end also it preferably extends beyond the entry end of the screen, for the purpose of affording means for supplying the discharge launder with a special or additional current of water when desired to insure the washing away of the oversize. This portion of the discharge launder is also shown broken away, because it may lead from any point.

The interior of the sieve being unobstructed, this launder, as well as the entry launder, can be located in the most advantageous positions. Thus, as to the discharge launder, it is desirable to locate it so that its upper side edges are adjacent the horizontal diameter of the sieve and close to the path

of the inner edges of the shelves 19, so that the shelves deliver the oversize material directly to this launder practically without any spilling back into the lower part of the sieve. The discharge launder is quite broad, and by virtue of the construction and mode of support of the sieve it may be made as deep as may be found advisable to avoid any danger of overflowing in event of a copious amount of wash water being employed. The form of the discharge launder may naturally be varied, but a desirable shape is the one illustrated, which lends itself well to sheet metal construction and in which the side portions of the trough simply slope inward and downward toward the center part, which may be curved.

The launders are shown supported on uprights 24, 25 outside the ends of the sieve, but it will be understood that these are merely indicative of any suitable means of support.

In order to prevent the blockading of the screening medium by particles which are too large to pass through but large enough to become caught in the openings, (this having been a serious problem in mining screens), I provide means for supplying water to the top of the sieve, so as to wash such particles back into the discharge launder. To this end I have shown two water pipes 25 extending longitudinally over the top at opposite sides of the center, these pipes being perforated so as to deliver the water downward in jets of suitable size. The water in the pipes being under appropriate head or pressure, a very effective clearing action is secured. This wash water falls into the discharge launder and serves to carry away the oversize material, in which it may be assisted by water supplied at the upper end of the launder; or the major portion of the water flowing in the discharge launder may come from beyond the entry end of the sieve, so that the oversize material is in effect deposited into and washed away by a stream of water flowing into and through the sieve.

The undersize material is received in a vessel 26, which is located beneath the sieve and comes up far enough on the sides thereof to catch all the material that passes through the meshes of the screening medium. It preferably slopes toward the discharge end of the sieve, and is provided with a discharge spout or pipe 27, which leads to any suitable point. It will be seen that all of the material has a substantially direct travel to and away from the screen. The pulp enters at one end, the under-size passes through the mesh of the screen and travels directly downward and forward, and the over-size is elevated slightly and also continues in the same general direction.

In operation, the ground ore and water flow into the sieve through the entry launder

and are distributed throughout the length of the tube. The mixture contains a sufficiently large amount of water and the particles of rock and mineral are loose, that is to say not of a sticky or adhesive consistency, so that the separation is effected quickly and thoroughly when the material encounters the screening medium; but the hard particles, particularly those which are too large to pass through, would tend to roll or slide on the surface of the fabric, thereby causing wear, and it is an important advantage to be able to minimize this action, and to limit the opportunity of slightly oversize particles to become caught in the meshes, by means of the elevating or interrupting devices projecting from the inner surface of the wire screen. By these latter devices the oversize material is carried up and deposited in the discharge launder, where it is carried away by the flow of water as described. As successive portions of the screen reach the top, they are automatically cleared of blockading particles by the jets from the overhead pipes. It will be observed that the oversize material is carried away at or above the level at which the material enters the screen, so that there is no loss of vertical height, which is frequently a matter of great importance in mill design. The entry launder and the undersize discharge may be brought even closer to the same level than shown, so that there need be little loss of vertical height as to this part of the material. It will be observed that the entering material passes into and the oversize material passes out of the screen in the same direction, and that the arrangement of the launders is such as to secure the greatest convenience and economy in construction and operation. It is important that the means for delivering the pulp to the sieve be located in the lower part thereof and close to the screen fabric, so as to minimize the fall and thereby contribute to the general object of avoiding wear.

Obviously numerous changes may be made in the construction of the screen without departing from the substance of the invention. The tubular or elongated form of the screen enables it to handle a considerable amount of material in a short space of time, and to increase the efficiency it may be made longer than shown. The size of the mesh of the screening medium is somewhat exaggerated in the drawing, for convenience of illustration. An obvious adaptation of the invention would be to unite a number of the sieves in axial alinement with screening mediums of progressively finer mesh, the discharge launder of each delivering to the sieve next in series.

What I claim as new is:

1. An ore-sizing screen, comprising, in 130

combination, a non-vibratory rotary tubular sieve supported to rotate on bearings which leave its interior and ends substantially unobstructed, means for conducting ore pulp 5 and distributing it lengthwise of the sieve, said means entering at one end and extending longitudinally of the sieve adjacent the lower portion thereof, an over-size launder at a greater height in the interior of the 10 sieve extending lengthwise thereof and inclining toward the opposite end from that at which the pulp enters, and means in the nature of shelves on the inside of the screen to limit the sliding of the ore and to elevate 15 the oversize material and dump it into the over-size launder.

2. An ore-sizing screen, comprising in combination a rotatably mounted tubular sieve open at the ends and interiorly so as 20 to afford passageway therethrough for the over-size material, an entry launder extending in at one end of the sieve, an over-size launder above the entry launder and inclined toward the opposite end of the sieve, 25 so as to carry the over-size material onward in the same direction, and means comprising shelves on the inside of the sieve adapted to limit the sliding of the ore thereon and to elevate the over-size material and to dump 30 it into the over-size launder.

3. An ore-sizing screen, comprising in combination a rotatably mounted tubular sieve open at the ends and interiorly so as to afford passageway therethrough for the 35 oversize material, means for conducting ore pulp in at one end of the sieve and for delivering it to the screen fabric throughout the length thereof, an over-size launder above said means and inclined toward the 40 opposite end of the sieve so as to carry the over-size material onward in the same direction, means comprising shelves on the inside of the sieve adapted to limit the sliding of the ore thereon and to elevate the over-size material and to dump it into the over-size launder, and means for applying a spray 45 externally to the top of the sieve above the over-size launder.

4. An ore-sizing screen, comprising in 50 combination a rotatably mounted tubular sieve open at the ends and interiorly so as to afford passageway therethrough for the over-size material, an entry launder extending in at one end of the sieve, an over-size 55 launder above the entry launder and inclined toward the opposite end of the sieve so as to carry the over-size material onward in the same direction, means comprising shelves on the inside of the sieve adapted to limit the sliding of the ore thereon and to elevate the over-size material and to dump it into the over-size launder, and means for supplying liquid to the over-size launder to wash away the over-size material.

5. An ore-sizing screen, comprising in

combination a rotatably mounted tubular sieve open at the ends and interiorly so as to afford passageway therethrough for the over-size material, an inclined entry launder entering and extending lengthwise of the 70 lower part of the sieve and provided with means for uniformly distributing the material throughout the length of the screen, an over-size launder also extending lengthwise of the screen, at a greater elevation than the entry launder, and inclined in the same direction, and means comprising shelves on the inside of the sieve adapted to limit the sliding of the ore thereon and to elevate the over-size material and to dump it into the 75 over-size launder.

6. An ore-sizing screen, comprising in combination a rotatably mounted tubular sieve open at the ends and interiorly so as to afford passageway therethrough for the 80 over-size material, an inclined entry launder entering and extending lengthwise of the lower part of the sieve, an over-size launder also extending lengthwise of the screen, at a greater elevation than the entry launder, and inclined in the same direction, means beneath the screen for receiving the under-size 85 material and conducting it onward in the same direction, and means comprising shelves on the inside of the sieve adapted to limit the sliding of the ore thereon and to elevate the over-size material and to dump it into the over-size launder.

7. An ore-sizing screen, comprising in combination a rotatably mounted tubular 90 sieve open at the ends and interiorly so as to afford passageway therethrough for the over-size material, an inclined entry launder entering and extending lengthwise of the lower part of the sieve, an over-size launder 95 also extending lengthwise of the screen, at a greater elevation than the entry launder, and inclined in the same direction, an under-size receptacle beneath the screen sloping forward and downward to an outlet toward the 100 discharge end of the screen, and means comprising shelves on the inside of the sieve adapted to limit the sliding of the ore thereon and to elevate the over-size material and to dump it into the over-size launder.

8. A metallurgical sizing screen comprising a rotary tubular sieve, and entry and over-size launders extending longitudinally therein, organized for substantially straight-line travel of the material to and beyond the 110 screen, in combination with devices distinct from the sieve mounted on the inside of the screen to limit rolling and capable in themselves of elevating the over-size and depositing it in the over-size launder.

9. An ore-sizing screen, comprising, in combination, a non-vibratory rotary tubular sieve, bearings supporting said sieve at lengthwise spaced points on its outer portion, an entry launder entering at one end of 115

said sieve and extending lengthwise thereof near the bottom to deposit the pulp thereon the full length of the sieve, an over-size launder extending lengthwise of the sieve above said entry launder, being inclined toward the opposite end of the sieve, and shelves projecting from the inside of the sieve and extending the full length thereof to limit the sliding of the ore and to elevate

the over-size material and dump it into the 10 over-size launder.

In witness whereof I have signed my name in the presence of two subscribing witnesses.

HERBERT A. MEGRAW.
